UNITED STATES PATENT OFFICE.

JOHN WILLIAM JONES, OF CLIFFORD, ILLINOIS.

CAR-UNCOUPLING DEVICE.

Application filed July 7, 1924. Serial No. 724,715.

To all whom it may concern:

Be it known that I, JOHN WILLIAM JONES, a citizen of the United States, residing at Clifford, in the county of Williamson 5 and State of Illinois, have invented certain new and useful Improvements in Car-Uncoupling Devices, of which the following is a specification.

This invention relates to car uncoupling 10 devices and is designed primarily to provide new and improved means, in a manner as hereinafter set forth, for disconnecting cars connected together by link connecting members.

15 The invention contemplates the provision of a drawbar having a hooked head projecting beyond the end sill of the car, and this head has pivotally connected to one side thereof at a point adjacent the bill of 20 the hook, a swinging link adapted to be swung upwardly across that portion of the hook overhung by the bill. A link connection is made between the free swinging end of the pivoted link, with a crank having 25 bearings in the body of the hook adjacent the point of connection with the drawbar, which crank extends outwardly to the side of the car where it terminates in a handle member. When a link connecting member 30 of another car is engaged over the hook of the drawbar, and it is desired to uncouple the same therefrom, the said handle is raised swinging the crank to lift the swinging end of the pivoted link which raises the 35 connecting link above the bill of the hook and allows the same to slip therefrom.

A further and final object of the invention is the provision, in a manner as hereinafter set forth, of a car uncoupling device which 40 is strong, durable, of easy operation, and inexpensive to manufacture.

The invention will be best understood from a consideration of the following detailed description taken in connection with 45 the accompanying drawings forming part of this specification, with the understanding that the invention is not confined to any strict conformity with the showing of the drawings but may be changed and modified 50 so long as such changes and modifications mark no material departure from the salient features of the invention as expressed in the appended claim.

In the drawings:

55 Figure 1 is a perspective view of the device embodying this invention showing a

portion of a coupling link engaged therewith.

Figure 2 is a similar perspective view of the device shown disengaging the coupling 60 link therefrom.

Referring now to the drawings in detail, wherein like numerals of reference indicate corresponding parts throughout the several views, a car floor is indicated in dotted lines 65 at 1 having the projecting spaced bumpers 2.

The device embodying this invention comprises an elongated flat drawbar 3 adapted to be secured upon or countersunk in the floor 1 and secured thereto by means of 70 bolts or screws (not shown) which are passed through the apertures 4 therein. One end of the drawbar 3 has formed integral therewith a head, indicated as a whole by the numeral 5. This head, as 75 shown, is relatively narrow and projects above and below the bar 3 where it is secured thereto forming the upper shoulder 6 at the end of the drawbar. This shoulder is rounded as is shown and has a bore transversely therethrough as at 7. The top portion of the head 5 is cut downwardly and forwardly from the shoulder 6 forming the downwardly inclined face 8 which cut in portion 8 is extended well into the body of 80 the head at the forward end thereof to form the overhanging or bill portion 9. This bill portion 9 and the upper part of the head integral therewith, extends a substantial distance above the shoulder 6 as shown. 85

Pivoted secured by means of a pin 10, to one side of the head 5 adjacent the upper edge and forwardly of the bill 9, is an arcuate link 11 the concave side 12 of which curves about the curved portion 13 of the 90 hook, and the free end of this link 11 has an aperture 14 therethrough to receive a connecting link 15 having a loop 16 at its inner end through which the crank 18 extends as shown in the figures.

100 The crank 18 is formed from a revoluble rod 19 a portion of which extends through the bore 7 in which it bears, and this rod 19 has its ends extended beyond the side of the platform 1 where they are bent at right angles to form the handles 20.

105 The link 11 is normally in the position shown in Figure 1 and when in this position the link 21 which forms a coupling element carried by another car, is engaged over the bill 9 of the hook and extends across the concave edge 12 of the link. When it is 110

desired to disconnect the link 21 from the hook the handles 20 are swung upwardly, consequently raising the crank arm 18 which carries with it the link 15 and the arcuate link 11. When the swinging end of the arcuate link 11 is raised, it will raise the link 21 from the curved face 13 of the hook until the swinging end of the link 11 is raised to the position above the bill 9, as indicated in Figure 2, whereupon the concave surface 12 at the pivoted end of the link will be substantially flush with the top of the bill and the link 21 will slip thereover to disconnect the cars.

From the foregoing description it may be seen that a very simple and efficient uncoupling device is provided by means of which cars can be uncoupled without the necessity of a brakeman getting between them.

Having thus described my invention what I claim is:

An uncoupling device of the character set forth comprising a drawbar, a head upon one end thereof formed to provide an upturned hook for engagement by a coupling member, a flat arcuate link having one end pivotally secured to the bill of said hook, and lying against and having the swinging end directed downwardly and inwardly, following the curvature of the inner portion of said bill, and means engaging with the free inner end of said link to lift the said inner end across the gullet of the hook to a point above the bill to raise the coupling member to a position where it will slip freely over the head.

In testimony whereof, I affix my signature hereto.

JOHN WILLIAM JONES.
